(57) **CLAIM**

The ornamental design for an adjustable mounting assembly of an agricultural work vehicle, as shown and described.

DESCRIPTION

FIG. 1 is a right front perspective view of an adjustable mounting assembly of an agricultural work vehicle; FIG. 2 is a bottom plan view of the adjustable mounting assembly; and,

FIG. 3 is a left rear perspective view of the adjustable mounting assembly.

In the drawings, the broken lines depict portions of a vehicle that form no part of the claimed design.
